(No Model.)

S. T. H. HOLT.
HEATING CHIMNEY.

No. 469,700.

Patented Mar. 1, 1892.

UNITED STATES PATENT OFFICE.

SAM. T. H. HOLT, OF PHILIPPI, WEST VIRGINIA.

HEATING-CHIMNEY.

SPECIFICATION forming part of Letters Patent No. 469,700, dated March 1, 1892.

Application filed November 4, 1891. Serial No. 410,880. (No model.)

To all whom it may concern:

Be it known that I, SAM. T. H. HOLT, of Philippi, in the county of Barbour and State of West Virginia, have invented certain new and useful Improvements in Heating-Chimneys; and I do hereby declare that the following is a full, clear, and exact description thereof, reference being had to the accompanying drawings, and to the letters of reference marked thereon, which form part of this specification, in which—

Figure 1 is a front view of my improved heating-chimney, the front wall being broken away to show the smoke and air flues. Fig. 2 is a vertical central section through the same transversely of the fire-places. Fig. 3 is a transverse sectional view on line 3 3, Fig. 1, looking down. Fig. 4 is a similar view on line 4 4, Fig. 1, looking up.

This invention is an improvement in the construction of fire-place chimneys whereby the fire-backs are utilized to heat air to be supplied to the rooms in the buildings; and the invention consists in the novel construction of the chimney with fire-places, smoke and air flues, and certain other novel details of construction and arrangement of parts, as will be fully understood from the following description and claims.

I propose to make the entire chimney-flues, &c., of masonry, either stone or brick, using metallic fire-backs for the open fire-places, however, so that no special pipe-fittings will be necessary nor expensive special work required to construct a chimney embodying my invention.

In the drawings, A B represent two open fire-place arches arranged back to back or directly opposite each other at the base of the chimney and communicating at top in the usual manner with smoke-flues a b, as shown. The arches are separated, however, but are provided with metallic fire-backs C C, and a close chamber D is thus formed between the fire-places, into which chamber fresh air is admitted through passages d d in the base of the chimney, at opposite sides thereof, and below the hearths and floor of the rooms the fresh air may be conducted to these passages through suitable pipes, if desired. The passages d are also provided with valves or

dampers for cutting off the supply of air, if desired.

E F designate heating-flues formed at the opposite sides of the smoke-flues and not communicating therewith, yet nearly inclosing the same, so as to utilize the heat from the walls of the smoke-flues to warm the air in the air-flues. These flues E F communicate at bottom through passages e f, respectively, with chamber D at opposite sides, as shown. The air-flues extend to the upper story or stories of the building and are provided with registered openings therein through which the heated air can escape into the rooms above, as desired. Registers may also be placed in the lower rooms to permit escape of heated air therein from chamber D.

G designates a partition plate or wall extending diagonally of chamber D between the fire-arches, and H is a door or valve in said partition, which, when closed, will shut off communication between air-flues E and F through chamber D and when opened will permit air to circulate freely through chamber D into either or both of the flues E F. Said valve may be adjusted by a rod h, as indicated in the drawings.

The operation of the device is as follows: Fires being kindled in the fire-places, the fire-backs and smoke-flues are heated, and the air in chamber D is also highly heated by contact with the fire-backs between which it circulates, and the heated air rises in flues E F, the heat being maintained or increased by contact with the heated walls of the smoke-flues. Fresh air entering chamber D is heated by contact with the fire-backs and rises into flues E F and is delivered into the rooms above whose registers are open. The passages e f might have valves or dampers, so that the entire volume of heated air could be diverted into either flue E or F; but by closing the registers in either flue the same effect will be produced. By having a valve which will diagonally divide or separate chamber D should fire only be in one fire-place the valve can be set so as to confine the heated air to one side, and also prevent the air from contacting with the cold fire-back, which, being of metal, is a good heat-conductor and would thus lessen the temperature of the air ascend-

ing to the air-flue. By this construction I utilize the heat of the fire-backs and smoke-flues to warm air to be supplied to the rooms of a building without any commingling of the air and products of combustion and without lessening the temperature of the fires or withdrawing heat from the lower rooms. The air-flues also being at sides of the smoke-flues and above the fire-arches preserve the symmetry of the chimney.

Having described my invention, what I claim as new, and desire to secure by Letters Patent thereon, is—

1. In a heating-chimney, the combination of 15 the fire-place having a metallic back C, a chamber D in rear thereof, a central masonry fire-flue *a* above the fire-place, masonry air-flues E and F above the fire-place and on each side of the fire-flue, communicating at 20 bottom with the chamber D through passages *e f*, respectively, and the air-inlet flue *d* to said chamber, substantially as described.

2. In a chimney-heater, the combination of the fire-place, the chamber in rear thereof,

the air-inlet thereto, the hot-air flues communicating therewith, the diagonally - arranged partition-plate in said chamber between the air-flues, and the door for opening in said partitions, substantially as specified.

3. The herein-described heating-chimney, 30 consisting of the front and rear fire-places having metallic backs, an air-heating chamber between the fire-backs, the smoke-flues communicating with the fire-places, the hot-air flues on each side of the smoke-flues, the 35 passages connecting said flues with the chamber, the air-inlet to said chamber, the diagonal partition therein, and the door in said partition, substantially as and for the purpose described.

In testimony that I claim the foregoing as my own I affix my signature in presence of two witnesses.

SAM. T. H. HOLT.
